UNITED STATES PATENT OFFICE.

EDWARD GOODFIELD, OF BROOKLYN, NEW YORK.

ILLUMINATED COSTUMER.

Application filed March 31, 1922. Serial No. 548,434.

To all whom it may concern:

Be it known that I, EDWARD GOODFIELD, a citizen of the United States, and a resident of the city of New York, borough of Brooklyn, in the county of Kings and State of New York, have invented new and useful Improvements in Illuminated Costumers, of which the following is a full, clear, and exact description.

10 This invention relates to improvements in costumers, particularly to an illuminated costumer, an object of the invention being to provide a device which will serve the double purpose of a costumer and floor lamp, and at 15 the same time, serve to illuminate articles hung upon the costumer so that they may be readily located.

A still further object is to provide a device of this character, which will be neat and attractive in appearance, simple and practical in construction, strong, durable and efficient in use, inexpensive to manufacture, and capable of being illuminated by the ordinary house lighting circuit.

25 With these and other objects in view, the invention consists in certain novel features of construction, and combinations and arrangements of parts, as will be more fully hereinafter described and pointed out in the 30 claim.

The accompanying drawing is a view mainly in front elevation, but partly in section of my improved costumer.

Referring in detail to the drawing, it will 35 be seen that I provide a relatively broad base 1, from which a standard 2 rises. The standard is formed with a longitudinally extending bore 3 throughout its entire length which receives a tubular wire conduit 4 for 40 the reception of an electric light wire, designated by the reference numeral 5.

Adjacent the upper end of the standard 2, the costumer is provided with the usual arrangement of ornamental garment receiving 45 hooks 6 secured to the standard in any approved manner. At its upper extremity the standard is formed with a reduced end 8 providing a shoulder 9 around the standard.

A substantially cup shaped globe receiving bracket 10 is fitted over the upper end of the standard and supported upon the shoulder 9. The wire 5 leads to an electric lamp socket 11 at the top of the standard, carrying a lamp 12. This lamp is normally 55 concealed, or rather the light of the lamp is subdued and filtered through a lamp globe

13 which surrounds the lamp. The lower end of this globe is reduced, as indicated at 14, to provide an annular shoulder 15 seating on the lip of the cup or bracket 10. The 60 globe 13 may of course be formed of any suitable transparent or translucent material, may be made in a variety of ornamental shapes, and may be suitably decorated to suit the trade; but will always have an annular enlargement 16 intermediate its top and bottom, the purpose of which enlargement is to overhang the hooks 6 to facilitate illumination of the articles suspended therefrom.

From the foregoing description it will be 70 apparent that I provide a device which may serve the double purpose of a costumer and floor lamp, at the same time providing means for exposing the position of garments upon the costumer at night.

75 Although I have illustrated the preferred embodiment of my invention, it will be obvious that numerous slight changes and alterations might be made in the general form and arrangement of the parts described 80 without departing from the invention, and hence I do not wish to limit myself to the precise details set forth, but shall consider myself at liberty to make such slight changes and alterations as fairly fall within the 85 spirit and scope of the appended claim.

I claim:

As a new article of manufacture, an illuminated costumer including a hollow standard, an exposed globular head on the top of the 90 standard, a lamp on the top of the standard within the globular head, garment hooks on the top of the standard just below the bottom of the head for suspending garments in position to be illuminated by light from the 95 globular head; said head comprising a shallow cup shaped bracket sleeving the top of the standard between the lamp and the hooks, said standard being of reduced diameter between the lamp and the hooks 100 to provide a shoulder for supporting the bracket, and said head also including a translucent dome having its lower edge supported by the upper edge of the bracket; the dome and bracket having substantially cylindrical walls of substantially the same diameter above and below the line of support of the globe by the bracket and said globe further having an annular enlargement intermediate its top and bottom and over- 110 hanging said hooks.

EDWARD GOODFIELD.
